195,402

RIGID AWNING

Bertrand N. Trombley, Bloomfield Hills, Mich., assignor to Republic Steel Corporation, Cleveland, Ohio, a corporation of New Jersey

Filed Dec. 27, 1961, Ser. No. 68,096

Term of patent 14 years

(Cl. D21—6)

FIG. 1 is a front perspective view of a rigid awning embodying my new design.

FIG. 2 is a side, sectional view thereof as taken from the indicated line 2—2 in FIG. 1.

I claim:

The ornamental design for a rigid awning as shown.

References Cited in the file of this patent

UNITED STATES PATENTS

2,873,487	Blanchard	Feb. 17, 1959
2,900,681	Becker	Aug. 25, 1959

OTHER REFERENCES

Popular Mechanics, July 1956, p. 182, items No. B & H.